UNITED STATES PATENT OFFICE.

ISAAC STRAUB, OF CINCINNATI, OHIO.

GRINDING-MILL.

Specification of Letters Patent No. 11,181, dated June 27, 1854.

To all whom it may concern:

Be it known that I, ISAAC STRAUB, of the city of Cincinnati, in the State of Ohio, have invented a new and useful Flouring, 5 Corn, and Corn and Cob Mill to be Propelled by Animal Power.

The following is an exact description, with the drawings referred to, by letters and figures, which symbols refer to like parts.

10 A, is a foundation of timbers and not properly a part of the mill. B, a suitable substantial plank or board floor well laid on beveled scantling, Figure 2, made in a circle Fig. 1, whose outside diameter is 22 feet 15 (all the sizes named in this specification are not arbitrary) and inclined upward, to the center, Fig. 2.

C, C, are side frame timbers 6 by 8 inches, and 20 feet long.

20 21 are cross-ties, for position, see Figs. 1 and 2.

27 is a supporting sill, see cross section, Fig. 2. In the center of this sill is a strong pin 22. At the ends of this sill are steadyng 25 truck-wheels 23, Fig. 3, (to steady when in operation); the center pin 22 and wheels 23, rest upon, and turn on the foundation 30, which is fastened on the ground work A.

The sill 27 is bolted to the side-timbers c, 30 at a point, see Figs. 2 and 3; immediately over this sill is placed the bridge-tree 15; in the center of this is placed the step and spindle 14; at a certain point, see drawings, is firmly fastened a face-plate, 33, whose 35 diameter is something less than the millstones; on its upper and outer edge is trued, to be at right angles to the axis of 14; near its outer edges is the pin 34, projecting upward. The lower mill-stone, 11, (which 40 is the runner) built on an iron plate having a hole to correspond with pin 34, drops on the pin, which is the driver; the plates on the lower side of mill-stone 11 is formed with a jog to drop on and over the face- 45 plate 33, as shown at 28; a like plate is on any number of runner stones, so that any numbers of pairs can be used for different purposes, each one being detached. At the 50 extreme upper end of 14 is the coupling 17, Figs. 2 and 3, for the object of extending the mill-spindle upward to floors overhead for the purpose of (when not grinding) ginning cotton, sawing and turning wood and iron, threshing grain, &c. The upper 55 mill-stone is so constructed with projections 25, see drawings for position, Figs. 2 and 4;

these projections rest on tram-blocks 24; when the projections 25 rest on 24, the faces of the millstones are in tram, exactly parallel, and never can get out of tram; these 60 tram-blocks 24 is a perpetual mode of and unerring trammimg, never to be attended to by the miller. These tram-blocks will exactly suit any number of upper mill-stones, all having the projections 25. The tram-blocks 24 stand on the framework, h, this again is secured to the posts, G. On the upper ends of the posts G, is a fixture 19, into which the boxing, or bearing of the upper end of the mill spindle 14, is carried, as 70 well as the hopper, 18. The rods 26, Fig. 3, are truss-rods to regulate and hold up the bridge-tree. At a proper place on the spindle 14, say two inches above the upper millstone 12, is noticed a cast-iron 13, Figs. 75 2, 3, 4, 5 and 6, whose vertical cross section is say 4 inches and diameter 8 inches, full of sharp teeth, all around the verge or outside, an oval hole through its center, this is passed on the spindle 14; see its position carried on a shoulder on 14, say 2 inches above this upper millstone 12. On its upper face is a circular incline-plane from a to g, see Figs. 2, 3, 4, 5, and 6; on the whole of this circular incline-plane is fastened with screw 80 bolts a wrought iron plate, whose end at a is a steel knife; the end at g, is movable, can be raised up (if wanted) and underlaid, to make less distance from g to a; when constructed, it will be remembered that 85 90 when in motion (for it runs with the mill spindle) the knife a is the head end. Outside and around 13, is a cast shell or ring 16, a little higher than 13; the inside of 16 is a series of straight lines, see o, o, o, o, o, Fig. 95 6, and its clear diameter is one inch greater than the points of the teeth on 13; the object of those straight lines o, o, o, o, o, is to produce a rolling process, which a smooth circle would not do, as the object is only to split and not pulverize (that is done by the mill-stone); on the ring 16 is placed a cover 44, and secured by bolts 45. At a suitable place on this cover is placed a tube near 3 inches in its clear diameter, see 31 (through which 100 the ears of corn pass); on the underside of this cover and near the opening of the tube 31 is fastened a steel knife, the knife a, on 13, just passing under this, the two knives forming a complete pair of shears by means of the adjustability of the plate at g; the 105 shears can be made to cut fast or slow to suit 110

the power used. After the ears of corn are sheared into short pieces, the rolling process splits fine enough, the whole passes on to the stone where it is pulverized all in one 5 operation.

The propelling power is in the revolving roller, *e*, this I make of cast iron 18 inches on the face, large diameter 26 inches, small nearly 23 inches; strong cast iron heads are 10 fixed in the several diameters, the whole being a case which I fill with heavy boulder rocks or their equivalents and calcined plaster Paris, or any grouting substance, weight and cheapness, being the object to 15 prevent slipping; the incline of the floor *B* corresponds with the conic form of the roller, the length of face, and great weight of charging as described, the object is obtained without the expense of cog-work as 20 formerly.

The roller *e*, is placed on the circular floor *B*, corresponding to a radius of eleven feet from the center-pin 22, to its greatest diameter; through the roller *e* passes the shaft *d*, 25 whose end rests on the cross-tie 21; at a proper point, the bevel wheel 7; this works

into the bevel pinion 8; this is on the counter shaft 20, on which is the spur wheel *g*; this turns pinion 10, and this being made fast to the mill spindle 14.

30

At 29, animal power is attached; on account of form and weight a strong contact on the floor *B*, causes a revolving of the millstone; with much power, the construction of the gearing turns the spindle 14, 150 35 revolutions for one round for the horse.

Having thus fully described the construction and operation of my mill, what I claim therein as new and desire to secure by Letters Patent, is—

40

The combination of the permanently adjusted tram blocks 24, for supporting the upper stone, and the bridge tree 15 which is adjustable at both its ends, for supporting and adjusting the spindle and the lower 45 stone or runner upon it, to the upper stone, substantially as described.

ISAAC STRAUB.
